UNITED STATES PATENT OFFICE.

JESSEE M. WHITE, OF PHILADELPHIA, PENNSYLVANIA.

VALVE-OPERATING MECHANISM FOR INTERNAL-COMBUSTION ENGINES.

1,073,882.

Specification of Letters Patent. Patented Sept. 23, 1913.

Application filed June 25, 1912. Serial No. 705,685.

To all whom it may concern:

Be it known that I, JESSEE M. WHITE, a citizen of the United States, residing at Philadelphia, in the county of Philadelphia and State of Pennsylvania, have invented 5 certain new and useful Improvements in Valve-Operating Mechanism for Internal-Combustion Engines, of which the following is a specification.

10 My invention relates to improvements in valve operating mechanism for internal combustion engines, the object of the invention being to provide an improved arrangement of oscillating levers fulcrumed between their 15 ends, and each end of the lever serving to engage a valve stem and control the opening and closing of the inlet and exhaust ports.

A further object is to provide an internal 20 combustion engine with an improved arrangement of valve operating eccentrics and improved means for transmitting motion thereto, whereby the operation of the valves are accurately timed, and the opening of the 25 valves rendered uniform with the employment of a minimum number of parts.

A further object is to provide improved 30 valve controlling mechanism which receives positive operation through the medium of a worm and worm wheel connecting the crank shaft of the engine with an eccentric shaft at right angles thereto at one end of the crank case and geared in a ratio of one to 35 two, and provide on said eccentric shaft a plurality of eccentrics mounted in suitable casings, so that they may be properly inclosed, and run in oil if desired, and provide oscillating levers operated by the eccentrics, each lever controlling the movement of two valves.

40 A further object is to provide an improved construction of valve operating eccentric in which ball bearings are employed between the eccentric proper and the ring, and the 45 latter in engagement with parallel walls of a reciprocating bar, whereby the latter is reciprocated without any oscillatory movement.

With these and other objects in view, the 50 invention consists in certain novel features of construction and combinations and arrangements of parts as will be more fully hereinafter described and pointed out in the claims.

55 In the accompanying drawings: Figure 1 is a view in side elevation illustrating my

improvements. Fig. 2 is a view in horizontal section on the line 2—2 of Fig. 1. Fig. 3 is a view in longitudinal section on an enlarged scale through the crank case. Fig. 4 60 is a view in section on the line 4—4 of Fig. 3. Fig. 5 is a view in section through one of the eccentric casings illustrating the eccentric and its bar in elevation. Fig. 6 is a view in section on the line 6—6 of Fig. 5, 65 and Fig. 7 is a view illustrating a modification.

1, represents a crank case which is made in two separable sections permitting ready access to the crank shaft 2 and connecting rods 70 3. On one end of the crank shaft, a balance wheel 4 is secured and on top of the crank case, a series of engine cylinders 5 are mounted. These engine cylinders are water-jacketed as illustrated at 6, and they 75 may be made in various ways, the T-head form shown being preferable but is for purposes of illustration only, as the invention is not limited to any particular kind of engine. The invention is, however, particularly applicable for engines having valve rods 7 extending down beside the cylinders, the exhaust valve rods being on one side of the engine, and the inlet valve rods on the other.

85 The valve rods 7 are connected to spring held valves so that when the rods 7 are moved upwardly, their valves will be opened and held open until said rods are permitted to descend. Below each pair of rods 7 is an 90 oscillating or rocking lever 10 fulcrumed between its ends on journals 11 which are supported in brackets 11^a on the crank case. The ends of these levers 10 are positioned below the lower ends of rods 7, so that when 95 the levers are oscillated in one direction, they move certain of said rods 7 upwardly and when oscillated in the opposite direction, move the other of said rods 7 upwardly. All of the oscillating levers 10 are 100 provided with depending arms 12. The depending arms 12 are secured to rods 13 and these rods 13 are pivotally connected by pins 14 with reciprocating bars 15. It is to be understood that there are four levers 10, four 105 rods 13, and four reciprocating bars 15 in a four-cylinder engine. Where the number of cylinders is greater or less, these parts will be proportioned thereto.

110 The bars 15 are each reciprocated by eccentrics 16 fixed to an eccentric shaft 17 supported in bearings 18 and extending

transversely of the crank case 1 at one end thereof. A worm wheel 19 is securely held on the shaft 17 by a jam nut 20 and meshes with a worm 21 on crank shaft 2. This worm wheel and worm are confined in a suitable casing 22 which is held together by bolts 23 and nuts 24, so that access may be had to the several parts as occasion may require.

10 The eccentrics 16 above referred to are arranged in pairs at opposite ends of the shaft 17, and they are positioned substantially opposite to each other, so that the timing of the valve openings is properly controlled. Each eccentric 16 is provided with a ring 25 concentrically positioned with relation to the eccentric and spaced therefrom by a circular series of balls 26, these balls running in raceways in the opposed surfaces 15 of the eccentric and the ring. The rings 25 bear against shoulders 27 on bars 15, and the bars 15 project through recessed guides 28 in the ends of casings 29. The casings 29 are curved in form and have curved 20 covers 30 secured thereon by bolts 31 and nuts 32. When the covers are in position, the casings have a circular form, and while they permit free movement of the eccentrics, they guide the bars 15 and permit only reciprocating movement of the latter, preventing any oscillating movement.

It is to be understood that the shoulders 27 are spaced apart a distance equal to the greatest diameter of ring 25, so that the 35 eccentric is free to move in its various positions at the same time maintaining the ring in contact with the shoulders without any lost motion.

In operation, the crank shaft 2 transmits 40 a positive rotary motion to shaft 17 in the ratio of two to one, and the eccentrics 16 cause the bars 15 and rods 13 to reciprocate, imparting an oscillating movement to levers 10. As these levers 10 oscillate or rock, 45 their ends engage the lower ends of the valve controlling rods 7, and elevate the latter, properly timing the opening and closing of the inlet and exhaust ports of the several cylinders. By this arrangement of parts, a 50 positive motion is transmitted uniformly from the crank shaft to the eccentric shaft, and from the latter to the several valves. The eccentric casings 29 are sufficiently tight to allow the eccentrics to run in oil if desired, and all of the working parts are fully incased to exclude dirt and grit.

In Fig. 7, I illustrate a modification in 60 which each valve rod 7 is provided with a separate rocker arm 33 pivotally supported at one end on a pin 34. The bars 35 corresponding to rods 13, have cams 36 thereon which engage rollers 37 on the arms 33 and cause them to oscillate as the bar is moved longitudinally.

35 Various slight changes might be made in

the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with an engine, and 75 valve moving rods positioned longitudinally of the engine and at opposite sides thereof, of oscillating levers fulcrumed between their ends and having their ends located in line with the rods, arms on said levers, rods connected to said arms, and eccentrics constructed to reciprocate said rods, substantially as described.

2. The combination with an engine, and 80 valve moving rods at opposite sides thereof, of oscillating levers fulcrumed between their ends and having their ends located in line with the rods, arms on said levers, rods connected to said arms, bars connected to said rods and having parallel shoulders, and eccentrics mounted to turn between the parallel shoulders on said bars, substantially as described.

3. The combination with an engine, and 95 valve moving rods at opposite sides thereof, of oscillating levers fulcrumed between their ends and having their ends located in line with the rods, arms on said levers, rods connected to said arms, bars connected to said rods and having parallel shoulders, eccentrics mounted to turn between the parallel shoulders on said bars, casings supporting and holding said bars against oscillating movement, and ball bearing rings forming 100 the outer surface of said eccentrics in contact with said shoulders, substantially as described.

4. The combination with an engine, and 110 valve moving rods at opposite sides thereof, of oscillating levers fulcrumed between their ends and having their ends located in line with the rods, arms on said levers, rods connected to said arms, eccentrics constructed to reciprocate said rods, a shaft on which all 115 of the eccentrics are mounted, a worm wheel secured on said shaft, a crank shaft driven by the engine, and a worm on said crank shaft meshing with the worm wheel, substantially as described.

5. The combination with an engine, and 125 valve moving rods at opposite sides thereof, of oscillating levers fulcrumed between their ends and having their ends located in line with the rods, arms on said levers, rods connected to said arms, bars connected to said rods and having parallel shoulders, eccentrics mounted to turn between the parallel shoulders on said bars, a shaft on which all 130 of the eccentrics are mounted, a worm wheel

secured on said shaft, a crank shaft driven by the engine, and a worm on said crank shaft meshing with the worm wheel, substantially as described.

- 5 6. The combination with an engine, and valve moving rods at opposite sides thereof, of oscillating levers fulcrumed between their ends and having their ends located in line with the rods, arms on said levers, rods connected to said arms, bars connected to said rods and having parallel shoulders, eccentrics mounted to turn between the parallel 30 shoulders on said bars, casings supporting and holding said bars against oscillating movement, ball bearing rings forming the outer surface of said eccentrics in contact with said shoulders, a shaft on which all of 35 the eccentrics are mounted, a worm wheel secured on said shaft, a crank shaft driven by the engine, a worm on said crank shaft meshing with the worm wheel, and a casing inclosing said first-mentioned shaft, said 40 worm wheel, and said worm, substantially as described.
- 10 7. The combination with an engine, and valve moving rods at opposite sides thereof, of oscillating levers fulcrumed between their 45 shoulders on said bars, casings supporting and holding said bars against oscillating movement, ball bearing rings forming the outer surface of said eccentrics in contact with said shoulders, a shaft on which all of the eccentrics are mounted, a worm wheel secured on said shaft, a crank shaft driven by the engine, and a worm on said crank shaft meshing with the worm wheel, substantially as described.
- 15 8. The combination with an engine, and valve moving rods at opposite sides thereof, of oscillating levers fulcrumed between their 50 shoulders on said bars, casings supporting and holding said bars against oscillating movement, ball bearing rings forming the outer surface of said eccentrics in contact with said shoulders, a shaft on which all of the eccentrics are mounted, a worm wheel secured on said shaft, a crank shaft driven by the engine, a worm on said crank shaft meshing with the worm wheel, and a casing inclosing said first-mentioned shaft, said 55 worm wheel, and said worm, substantially as described.
- 20 9. The combination with an engine, and valve moving rods at opposite sides thereof, of oscillating levers fulcrumed between their 60 shoulders on said bars, casings supporting and holding said bars against oscillating movement, ball bearing rings forming the outer surface of said eccentrics in contact with said shoulders, a shaft on which all of the eccentrics are mounted, a worm wheel secured on said shaft, a crank shaft driven by the engine, a worm on said crank shaft meshing with the worm wheel, and a casing inclosing said first-mentioned shaft, said 65 worm wheel, and said worm, substantially as described.
- 25 10. The combination with an engine, and valve moving rods at opposite sides thereof, of oscillating levers fulcrumed between their 70 shoulders on said bars, casings supporting and holding said bars against oscillating movement, ball bearing rings forming the outer surface of said eccentrics in contact with said shoulders, a shaft on which all of the eccentrics are mounted, a worm wheel secured on said shaft, a crank shaft driven by the engine, a worm on said crank shaft meshing with the worm wheel, and a casing inclosing said first-mentioned shaft, said 75 worm wheel, and said worm, substantially as described.

ends and having their ends located in line with the rods, arms on said levers, rods connected to said arms, bars connected to said rods and having parallel shoulders, eccentrics mounted to turn between the parallel 30 shoulders on said bars, casings supporting and holding said bars against oscillating movement, ball bearing rings forming the outer surface of said eccentrics in contact with said shoulders, a shaft on which all of 35 the eccentrics are mounted, a worm wheel secured on said shaft, a crank shaft driven by the engine, a worm on said crank shaft meshing with the worm wheel, and a casing inclosing said first-mentioned shaft, said 40 worm wheel, and said worm, substantially as described.

In testimony whereof I have signed my name to this specification in the presence of two subscribing witnesses.

JESSEE M. WHITE.
